FOLDING HIGH CHAIR

Louis Pokorny, Jr., Ronkonkoma, N. Y.

Application August 27, 1954, Serial No. 32,052

Term of patent 14 years

(Cl. D15—1)

Fig. 3.

Fig. 5.

Fig. 4.

I claim:

The ornamental design for a folding high chair, as shown.
